[57] ABSTRACT

This implement comprises an upright standard and a cross bar which extends at right angles to the standard and is adjustable to different heights along the standard and also in its axial direction so that its tool-carrying end may be extended to different distances from the standard. The invention provides that the cross bar is made of a tubular shape with closed ends which are connected to each other by bracing means, for example, tie rods, which extend longitudinally through the hollow inside of the cross bar and at least one of which is connected to at least one end of the cross bar at a point above the longitudinal axis of the cross bar so that, when this bracing means is tightened on the outside of one end of the cross bar, the tool-carrying part will be given a biasing tension which tends to curve this part upwardly and thereby counteracts the tendency of this part to bend downwardly under its own weight and the weight of the respective tool thereon. This biasing tension of the cross bar may be adjusted in accordance with the weight of the particular tool. By providing several tie rods or similar bracing means within the cross bar and connecting them at different points to the ends of the cross bar, and adjusting them axially to different tensions, the cross bar may also be bent in lateral directions.

IMPLEMENT FOR MEASURING OR MARKING WORKPIECES

The present invention relates to an implement for measuring or marking workpieces which comprises an upright standard and a cross bar which is adjustable along this upright and also substantially horizontally in the direction of its longitudinal axis relative to the standard and is substantially hollow between its opposite ends and provided at the inside thereof with bracing means which extend from one of its closed ends to the other and are adapted to be variably tightened so as to insure that the axis of the cross bar will extend in a straight direction.

Such implements which are also known, for example, as three-dimensional layout devices are provided with a base which is slideable along the upper surface of a work table and carries an upright measuring standard which extends vertically to the upper surface of the work table and on which a slide member is adjustable to different heights which, in turn, permits the cross bar to be adjusted to different effective lengths in its axial direction parallel to the upper surface of the work table. Since for marking or measuring large workpieces, for example, car bodies, such a work table may have a very large size, for example a length of 6 meters and a width of 2.5 meters, the cross bar which carries a tool head on one end may also be required to have a considerable length. When such a cross bar is shifted horizontally in the slide member, the disadvantage occurs that the farther its end carrying the tool head is spaced from the slide member, the more this end will bend downwardly so that the actual height of the tool head will then no longer correspond to the height of the cross bar as indicated on the standard. This disadvantage may be overcome by making the cross bar of such an initially curved shape that, regardless of the distance to which the tool head is extended from the standard and the slide member thereon, it will always remain within the same horizontal plane. This will be true, however, only if the weight carried by the cross bar always remains the same which, however, is often not the case since such an implement is usually provided with several tools of different weights which are to be secured to the tool head in place of each other. Furthermore, even if the weight of the respective tool acting upon the tool head is always the same, it is very difficult to curve the cross bar so accurately that its inherent resilience will compensate the difference in weight caused by varying its effective length.

In order to eliminate the marking or measuring inaccuracies of such an implement the cross bar of which is not initially curved upwardly as mentioned above or to eliminate the difficulties of producing such a curved cross bar, an implement has already been designed which is of a type of construction as mentioned at the beginning and is provided at the inside of the hollow cross bar with a bracing element consisting of a relatively thick rod which extends longitudinally from one closed end of the cross bar to the other and has piston-shaped enlargements on its opposite ends which are in engagement with the inner peripheral wall of the cross bar. Approximately at the center of its length, the wall of the hollow cross bar is provided with a setscrew which when tightened presses transversely against the longitudinal rod. Since the piston-shaped ends of this

rod engage upon the inner wall of the cross bar, the screw when tightened is supposed to bend the cross arm between its ends in the direction opposite to the tendency of the extended cross arm to bend under its own weight and the weight of the tool thereon. Additional screws which connect the cross bar to the piston-shaped ends of the longitudinal rod limit any movements of these ends relative to the cross bar.

It is one of the disadvantages of this manner of bracing the cross bar that, in order to produce the resilient bending forces upon the cross bar, the longitudinal rod at the inside of the cross bar has to be relatively thick and solid. Considering its length, this rod is therefore also very heavy, whereas properly it should be as light as possible in order to reduce as much as possible the tendency of the cross bar to bend downwardly due to its own weight and the weight of the tool thereon. Furthermore, since in order to be able to bend the cross bar by the pressure of the central set-screw laterally against the longitudinal rod at the inside of the cross bar, the wall of the cross bar has to be made relatively thin, there is considerable danger that the setscrew when tightened will cause the cross bar to be permanently and not merely resiliently deformed.

It is an object of the present invention to provide an implement of the type as mentioned at the beginning which is provided with bracing means at the inside of the hollow cross bar which are adapted to counteract the tendency of the cross bar and the tool on its free end to bend downwardly from the upper surface of the work table when the cross bar is shifted in its axial direction so as to increase its effective length from the slide member in which it is supported on the standard. A further object of the invention is to provide such bracing means which are of a simple construction and a light weight and may be easily adjusted, for example, in accordance with different weights of the tools which may be removably secured in place of each other to the tool holder on the free end of the cross bar.

For attaining these objects, the invention provides these bracing means to consist of at least one bracing element, preferably in the form of a tension element such as a tie rod or similar means, which acts upon the axially outer ends of the cross bar and the bracing action of which upon the cross bar may be easily increased or reduced at will. By these bracing means it is possible in accordance with the principle of prestressed concrete to apply a lower or higher longitudinal force eccentrically upon the cross bar and thereby to tend to curve the longitudinal axis of the latter to different extents so as to counteract the tendency of the tool-carrying end of the cross bar to bend downwardly and to insure that the measuring or marking point of the tool which is secured to the tool head on the end of the cross bar will remain with a sufficient accuracy within the same horizontal plane regardless of the length to which the cross bar is extended from the slide member which supports it rigidly on the standard.

The bracing means according to the invention may consist of relatively thin and light elements since they only have to transmit forces in their longitudinal directions, while no elastic or other forces have to be exerted in the transverse direction of the cross bar. The tension or pressure is applied upon the outer ends of the cross bar and there are no adjusting elements which

extend transversely through the cross bar and might permanently deform its cross-sectional shape. It is therefore not only possible to make the bracing elements in toto thinner and of a lighter weight than the bracing element which was previously required but the walls of the cross bar may also be made relatively thin. The advantages of the invention are especially great if the bracing means merely consist of tension elements and if it is only necessary to apply a tension upon the ends of these elements. It is, however, also possible according to the invention to attain the desired longitudinal bracing effect by pressure elements which do not necessarily have to be considerably thicker than the tension elements if, for example, by providing several transverse supports within the cross bar at short distances from each other, the unsupported length of these pressure elements within which buckling could occur is made very small.

According to an improved embodiment of the invention, the hollow cross bar is provided with at least two bracing elements which are located therein above each other and one of which has at least one end acting upon one axial end of the cross bar at a level above the longitudinal axis of the cross bar, while the other bracing element has at least one end acting upon an axial end of the cross bar at a level below this axis. If both bracing elements are tightened, the upper element will counteract the lower element within a vertical plane so that both bracing elements will be under an initial tension or pressure, whereby ineffective initial motions due to an inherent expansion or compression of the material of the bracing elements will be prevented. When these bracing elements are adjusted, they will therefore immediately act upon the cross bar and affect the direction of its longitudinal axis and do not at first need to overcome a certain play in their longitudinal directions.

According to another important feature of the invention, the hollow cross bar contains at least two bracing elements laterally adjacent to each other within the same horizontal plane. At least one end of one of these bracing elements acts upon the corresponding axial end of the cross bar at a point at the left side of the longitudinal axis of the cross bar, while at least one end of the other bracing element acts upon the respective axial end of the cross bar at a point at the right side of the central vertical plane of this bar. By tightening these bracing elements to different extents, it is possible to affect the straightness of the cross bar also within a horizontal plane which is important especially for compensating tolerances of manufacture of the cross bar.

Another important feature of the invention consists in providing at least three bracing elements preferably in an isosceles triangular arrangement within the hollow cross bar so that two of these elements are disposed laterally adjacent to each other within the same transversely horizontal planes. Such a triangular arrangement of the bracing elements permits not only an adjustment of the desired initial tension or pressure so as to counteract the tendency of the cross bar to bend downwardly but also an adjustment of the direction of the cross bar within a horizontal plane.

If the bracing means in the form of one or more elements are disposed parallel to the longitudinal axis of the cross bar and are tightened, the cross bar will be

bent to an arcuate shape. It has now been found that the best possible compensation of the curvature of the cross bar which is caused by its weight and the weight of the tool thereon may be attained if by being 5 tightened at its ends the cross bar will be initially bent to a parabolic curvature which, as seen from its end carrying the tool head, is at first very flat and only thereafter increases in slope toward the other rear end. Another very important feature of the invention for 10 attaining such a parabolic shape consists in mounting the bracing element or at least one of the bracing elements to extend at an oblique angle to the longitudinal axis of the cross bar. In a preferred embodiment of the invention the point of connection of the obliquely extending 15 bracing element or of each of these elements to the free end of the cross bar carrying the tool head is located within a lower plane than its point of connection to the other end of the cross bar. Thus, for example, the first 20 point of connection may be located at the level of the longitudinal axis of the cross bar, while the second point of connection at the rear end of the cross bar may be located above this axis. The parabolic curvature of the cross bar then merges into a straight line near the free end of the cross bar carrying the tool head.

It has further been found that, when the effective 25 length of the cross bar is increased, it will — due to its inherent rigidity — remain at first straight and will start to curve downwardly only at a certain distance from its rigidly clamped part. For ideally compensating this 30 bending of the cross bar, the biasing curvature of the latter would have to extend inversely corresponding to the normal curvature, that is, from the free end of the cross bar at first horizontally and, for example, only 35 subsequent to its center in the form of an upwardly directed parabolic curve. This ideal shape of the cross bar would be attainable if the oblique longitudinal bracing means would extend, for example, only up to a central part of the length of the cross bar where the 40 bracing means would end on the central longitudinal plane of the cross bar. This, however, can only be attained with difficulties since it would then be necessary to provide and secure a special central support within the cross bar. According to a further embodiment of 45 the invention, a compromise solution of this difficulty may be attained by placing the axial point or points of connection of the oblique bracing means to the free end of the cross bar carrying the tool head in a position underneath the level of the longitudinal axis of the cross bar, while the point or points of connection of these bracing means to the other end of the cross bar are located above this plane. In this manner it is possible 50 to attain a biasing curvature of the cross bar of a slightly wavy shape insofar as it extends at first in accordance with the ideal parabolic shape, while the subsequent length of the cross bar toward its free end will be slightly wavy and deviate only very slightly from the desired straight shape. The present invention therefore attains the almost ideal conditions without requiring 55 any additional structural means. These parabolic or first parabolic and subsequently slightly wavy biasing curvatures are only attainable because the longitudinal bracing means according to the invention are located at the inside of the cross bar and can thus extend obliquely 60 from one end of the cross bar to which they are connected above the longitudinal axis of this bar to the other end to which they are connected below this axis.

If the bracing means consist of several bracing elements, the positions of their axial connecting points are determined by the resultant vector of these points. If three bracing elements are provided in a triangular formation in which two of these elements are located within the upper part and the third within the lower part of the cross-sectional area of the inside of the cross bar, it is advisable that only the two upper elements extend obliquely to the longitudinal axis of the cross bar, while the lower element extends substantially parallel to this axis.

The features and advantages of the present invention will become further apparent from the following detailed description thereof which is to be read with reference to the accompanying diagrammatic drawings, in which:

FIG. 1 shows a side view of the implement according to the invention and of a part of the work table;

FIG. 2 shows a longitudinal section of one end of the cross bar of the implement according to FIG. 1 but on a larger scale;

FIG. 3 shows a cross section which is taken along the line III — III of FIG. 2;

FIG. 4 shows a longitudinal section of the cross bar according to FIGS. 2 and 3, and a compression and tension diagram therein;

FIG. 5 shows an illustration similar to FIG. 4 of the cross bar according to a modification of the invention;

FIG. 6 shows a diagram of the line of downward deflection of a cross bar due to its weight; while

FIGS. 7 to 10 show diagrams of different biasing lines along which the cross bar may be bent so as to compensate its normal deflection; namely, FIG. 7 a biasing line of the ideal parabolic shape, FIG. 8 a biasing line of a convex shape which deviates considerably from the ideal line, FIG. 9 a biasing line of a parabolic shape which is more similar to the ideal line, and FIG. 10 a biasing line of a wavy shape which is closely similar to the shape of the ideal line.

In the drawings, FIG. 1 illustrates a work table 1 which has an upper surface 2 upon which the work-piece is placed or clamped which is to be measured or marked. At one end of the opposite lateral surfaces 3 and 4 of work table 1 a pair of flat bars 5 are secured which are provided with corresponding recesses 6 into which a locking member 8 on each end of a guide bar 7 is adapted to engage which extends across the work table 1.

Along the guide bar 7 the implement according to the invention is guided which is generally designated by the numeral 10. It comprises a base 11 which is slidable on the work table 1 and on which an upright supporting means including a standard 12 is mounted which extends vertically to the upper surface 2 of work table 1. The supporting means further comprises a slide member 13 which is adjustable to different heights along the standard 12 and forms a horizontal guide means for a cross bar 14 which extends through this slide member and is adjustable thereon in its axial direction parallel to the upper surface 2 of work table 1. The front end of this cross bar 14 is provided with a tool head 15 for holding a measuring or marking tool 16 which may also be exchanged for a different tool. The rear end is located on the other side of guiding slide member 13. Standard 12 is provided with a groove into which a scale bar 17 is fitted, and cross bar 14 is

likewise provided with a groove into which a scale bar 23 is fitted. Slide member 13 is further provided with a vernier 24 for reading its vertical position on scale bar 17 and with a vernier 25 for reading the horizontal position of cross bar 14 on scale bar 23.

As illustrated in FIGS. 2 and 3, cross bar 14 has a rectangular tubular shape and its opposite ends are closed by end plates 29. Above its longitudinal axis 77, cross bar 14 contains within its inner upper part two bracing elements in the form of tie rods 30 and within its inner lower part underneath the axis 77 one bracing element likewise in the form of a tie rod 31. These three tie rods extend along straight lines from the tool supporting front end to the rear from one to the other end of cross bar 14 and are provided on both ends with threaded parts 32 which project through bores in the end plates 29. As may be seen in FIG. 3, the three tie rods 30 and 31 are disposed relative to each other so as to be located at the corners of an isosceles triangle. The outer side at least of the left end plate 29 carries presetting means in the form of nuts 33 which are screwed upon the threaded end parts 32 of the tie rods and permit these rods to be differently prestressed from the outside so as to bend the tubular cross bar 14 upwardly, and then to be locked permanently for compensating its tendency to bend downwardly under its own weight and the weight of the tool 16. Due to the triangular arrangement of the three tie rods, it is also possible to bend the cross bar 14 slightly in lateral directions if this should be desirable, especially for compensating tolerances of manufacture of cross bar 14.

FIG. 4 illustrates this cross bar 14 once more diagrammatically. The points on which the tie rods 30 and 31 are to be tightened at the left end 73 of cross bar 14 which extends through the slide member 13 as shown in FIG. 1 are indicated at 75, while at the other end 74 which carries the tool head 15 these points are indicated at 76. The nuts 33 as shown in FIG. 2 only need to be screwed upon one end of the tie rods, for example, the end 73, while the other ends of the tie rods may be screwed into the other end plate 29 or be rigidly secured thereto. This other end plate may also be integral with the tool holder 15.

FIG. 5 illustrates a modification of the tubular cross bar 14 which likewise contains three tie rods 30 and 31 in a triangular arrangement similar to that as shown in FIGS. 2 to 4 so that the two tie rods 30 are located within the upper part above the longitudinal axis 77 of cross bar 14 and one tie rod 31 within the lower part below the axis 77. From the left end 73 of cross bar 14 toward the tool head 15 the two upper tie rods 30 extend obliquely downwards approximately to the level of the longitudinal axis 77 of cross bar 14, while the lower tie rod 31 extends parallel to the axis 77 like the lower tie rod in FIGS. 2 to 4. The points of connection 76 of the upper tie rods 30 to the end 74 of cross bar 14 which carries the tool head 15 are therefore disposed on a lower level than their points of connection 75 to the opposite end 73 of the cross bar. The same applies if only the resultant vector of the three tie rods and the three points of connection at each end is considered. The four pressure and tension diagrams A, B, C and D in FIG. 5 illustrate that, due to this course or arrangement of the tie rods, it is possible to tighten them so as

to provide the cross bar 14 with a parabolic curvature the first part of which following the end 74 is very flat, while the subsequent part increases in slope toward the end 73. By differently adjusting the two upper tie rods 30 it is also possible to correct small inaccuracies of the cross bar 14 within a horizontal plane.

If the adjustment of the shape of cross bar 14 is carried out in such a manner that the lower tie rod 31 is provided with a small initial tension, it will only be necessary for a further later adjustment to turn the nut 33 of this tie rod in order to attain the desired shape of the cross bar.

Of course, in place of tie rods, it is also possible to provide other suitable kinds of tension elements, for example, cables. Furthermore, for attaining a desired parabolic shape of cross bar 14, it is also possible to provide the tension elements in other inclined positions, for example, so that the axial points of connection 76 of the obliquely extending elements 30 on the end 74 of cross bar 14 adjacent to the tool head 15 will be located within a plane underneath the longitudinal axis 77 of cross bar 14.

In each of FIGS. 6 to 10, the solid line indicates on a scale of 1 to 10 the theoretic horizontal direction of cross bar 14, while the dot-and-dash line indicates on a scale of 100 to 1 the course of a line along which it is bent within a vertical plane so as to have the required initial tension.

In FIG. 6, the dot-and-dash line 79 indicates at the points 3 to 13, respectively, the extent to which the tool-head end of the unbraced cross bar 14 is bent when it projects to each of eleven different positions from the slide member 13, as shown in FIG. 1. Cross bar 14 extends, for example, within the slide member 13 up to the position 78 between the points 2 and 3. Due to its inherent rigidity, cross bar 14 will remain straight when being pulled out of slide member 13 up to the point 7. However, when pulled out beyond this point, it will bend downwardly so that its right end will be located at the points 8 to 13, respectively. This results in a parabolic curvature of cross bar 14 from the point 13 to the point 7 from which it extends horizontally up to the point 1.

For compensating this curvature ideally, it would be necessary to prebend the cross bar 14 to a shape as indicated in FIG. 7 by the dot-and-dash line 80, that is, the right part from the point 13 to the point 7 in a straight direction and then to the left end from the point 7 to the point 1 along an upwardly directed parabolic curve which inversely corresponds to the curved line 79 between the points 13 and 7 in FIG. 6. This ideal line 80 of the curvature of cross bar 14 would be attainable if its longitudinal bracing means would extend obliquely from the left end only up to a central part of the length of the cross bar and would end at that point on the longitudinal axis of the cross bar. This can, however, be attained only with difficulties since the cross bar would then require a special support at its center.

If the bracing elements extend parallel to the longitudinal axis 77 if the cross bar within the upper part of the hollow inside thereof, the cross bar will be bent downwardly along an arc to a convex shape, as indicated in FIG. 8 by the dot-and-dash line 81. It will be seen that the right upwardly curving part of line 81

deviates from the corresponding straight part of the ideal line 80 as shown in FIG. 7.

If the longitudinal bracing means extend from the upper left end obliquely toward the right up to the longitudinal axis 77 of the cross bar, the latter will be parabolically prebent up to its right end, as indicated by the dot-and-dash line 82 in FIG. 9. This prebent curvature is also not as good as desirable because it is curved too strongly especially between the points 3 and 7.

If, however, the longitudinal bracing means extend from the upper left obliquely downwards toward the right to a point slightly below the longitudinal axis 77 of the cross bar, the latter will be prebent to a slightly wavy shape, as indicated by the dot-and-dash line 83 in FIG. 10. The left part of this curved line extends from the points 1 to 7 in accordance with the corresponding part of the ideal parabolic line 80 as shown in FIG. 7, while the wavy right part of line 83 deviates only very slightly from the ideal straight line. The partly parabolic and then slightly wavy line 83 as shown in FIG. 10 is therefore the most similar to the ideal line according to FIG. 7.

The bracing possibilities according to FIGS. 9 and 10 are possible only because the longitudinal bracing means according to the invention are located at the inside of the tubular cross bar so that the obliquely extending bracing means may be connected at one end above the axis 77 and at the other end below the axis 77 of the cross bar to the respective axial ends of the latter.

Although my invention has been illustrated and described with reference to the preferred embodiments thereof, I wish to have it understood that it is in no way limited to the details of such embodiments but is capable of numerous modifications within the scope of the appended claims.

Having thus fully disclosed my invention, what I claim is:

1. An implement for measuring workpieces, comprising upright supporting means including horizontal guide means; a tubular cross bar having an axis, a tool supporting front end, and a rear end, said cross bar being supported in said guide means intermediate said ends for horizontal movement in the direction of said axis between displaced positions in which said tool supporting end is spaced different axial distances from said guide means so that said tool supporting end is urged by the force of gravity downward out of a desired horizontal level to different degrees depending on the length of the respective distance; and bracing means including at least one bracing element located within said tubular cross bar spaced from said axis and having a cross section substantially smaller than the cross section of said tubular cross bar, and opposite ends connected with said front and rear ends of said cross bar, respectively, said bracing element extending along a straight line directly between said front and rear ends, and adjustable presetting means at least at one end of said bracing element abutting said cross bar so that said bracing element is tensioned along said straight line, said presetting means including means holding said bracing element permanently prestressed for holding said cross bar permanently curved irrespective of the length of said axial distances so that the effect of the force of gravity is substantially compensated and said tool sup-

porting end is substantially located at said desired horizontal level irrespective of the position of said cross bar relative to said guide means.

2. An implement as claimed in claim 1 wherein said bracing means include at least two bracing elements located within said tubular cross bar, and being permanently prestressed by said presetting means, at least one end of one of said bracing elements being connected with the corresponding end of said cross bar at a point located above the horizontal level of said longitudinal axis of said cross bar, and at least one end of the other bracing element being connected to said one end of said cross bar at a point below the horizontal level of said axis, the other ends of said bracing elements being connected with the other end of said cross bar, said prestressed bracing elements being adapted to counteract each other.

3. An implement as claimed in claim 1 in which said bracing means include at least two bracing elements disposed laterally adjacent each other in a direction transverse to said axis, at least one end of one of said bracing element acting on the corresponding end of said cross bar at a point at the left side of a vertical plane passing through said axis of said cross bar, and at least one end of the other bracing element acting upon the corresponding of said cross bar at a point at the right side of said central vertical plane.

4. An implement as claimed in claim 1 in which said bracing means include at least three bracing elements prestressed by said presetting means and extending within said cross bar between the ends of the same, the ends of said bracing element at least at one end of said cross bar being located at the corners of an imaginary triangle, at least two of said bracing elements being disposed laterally adjacent each other in a direction transverse to the direction of said axis, and at opposite sides of a central vertical plane passing through said axis of said cross bar.

5. An implement as claimed in claim 4 in which at least said ends of said bracing element are located at the corners of an imaginary isosceles triangle.

6. An implement as claimed in claim 4 in which one

end of each of said two laterally adjacent bracing elements are connected with the corresponding end of said cross bar at the level above said axis of said cross bar, and one end of the third bracing element is connected with the corresponding end of said cross bar at a level below said axis of said cross bar.

7. An implement as claimed in claim 6 in which said two laterally adjacent bracing elements extend within said cross bar slanted at substantially equal oblique angles to said axis of said cross bar at least a greater part of the length of said bracing elements being located above said axis, and wherein said third bracing element extends substantially parallel to said axis of said cross bar.

15 8. An implement as claimed in claim 1 wherein said one bracing element extends within said cross bar slanted at an angle to said axis of said cross bar.

9. An implement as claimed in claim 8 wherein the greater part of the length of said slanted bracing element is located above said axis of said cross bar.

10. An implement as claimed in claim 8 wherein one end of said slanted bracing element is connected with said tool-supporting end of said cross bar, and the other end of said bracing is connected with said rear end of said cross bar, said one end of said bracing element being disposed in a lower position than said other end of said bracing element.

20 11. An implement as claimed in claim 10 wherein said one end of said bracing element is disposed below the horizontal level of said axis of said cross bar, and wherein said other end of said bracing element is disposed above the horizontal level of said axis of said cross bar.

30 12. An implement as claimed in claim 11 wherein said bracing element includes a tie rod having ends connected with said front and rear ends of said cross bar, at least one of said ends being threaded and extending through the corresponding end of said cross bar, and wherein said presetting means comprise a nut screwed from the outside of said cross bar on said threaded end and abutting the corresponding end of said cross bar.
